Attorney.

UNITED STATES PATENT OFFICE.

GEORGE H. HARDMAN, OF FALL RIVER, MASSACHUSETTS, ASSIGNOR TO HARDMAN RAILROAD TIE CORPORATION, A CORPORATION OF DELAWARE.

TIE.

1,275,021.

Specification of Letters Patent.

Patented Aug. 6, 1918.

Application filed December 12, 1917. Serial No. 206,812.

To all whom it may concern:

Be it known that I, GEORGE H. HARDMAN, a citizen of the United States, residing at Fall River, in the county of Bristol and 5 State of Massachusetts, have invented certain new and useful Improvements in Ties, of which the following is a specification.

My invention relates to railroad ties and more particularly to the reinforcing clamping members individually and in combination with the tie.

For the prevention of buckling, splitting, or other damage to the tie, as well as for the reinforcement of the same, whether the tie 15 be an integral wooden structure, a built up structure, or a combination of wood and mastic, there have been employed clamping members whose bodies were seated in transverse holes in the tie, and whose diverging 20 ends have been bent to form clamping arms embracing the tie. These members were formed by placing side by side two metallic rods and welding together their intermediate portions to form an integral body, 25 leaving the unwelded ends to constitute bendable arms. In actual use these members have become split or broken at or adjacent the welded body portion when subjected to extreme strain. It has also been attempted 30 to construct the members by mechanically bifurcating the ends of a solid bar to form the body and arms but this has been mechanically difficult and excessively expensive.

35 The objects of my invention are to combine with a tie a reinforcing and clamping member that will be free of the enumerated weaknesses, and disadvantages, and which will be simple and inexpensive to construct 40 and apply.

My invention consists, therefore, in the means for producing the results above specified substantially as hereinafter described and claimed, and as shown in the accompanying drawings which form a part of 45 this specification, wherein—

Figures 1 and 2 are side and end elevations respectively of a reinforcing clamping member for employment in the tie,

Fig. 3, a perspective view of a tie equipped 50 with a plurality of such members,

Fig. 4, a section on line 4—4 of Fig. 3, and

Figs. 5 and 6, like sections of modifications.

Like characters of reference indicate like parts throughout the views.

In the embodiment of my invention herein illustrated is a railroad tie comprising either an integral wooden block, a plurality 60 of blocks or layers of wood or other material, or a composition of mastic and wood, having upper, lower, and side faces respectively. A series of holes or openings *b* extend transversely of the tie for the reception of the reinforcing clamping elements *C*. In detail the latter are formed as follows. Two metallic rods, semicircular in cross section, have their flat faces placed in contact with each other and their intermediate portions are then twisted about each other forming the spirals *d*. The non-twisted portions *c* are afterward bent to form clamping arms.

The length of these bendable clamping 75 arms is determined by the contour, magnitude, or material of the tie in which the device is to be used. The number of spirals or twists *d*, while also governed somewhat by the above conditions, are preferably extended throughout the length of the hole *b*. When it is desired to clamp the entire area of the tie, as shown in Figs. 3, 4, and 6, the arms *c* have their inner end portions *f* in contact with the sides of the tie, and their extremities *g* in contact with the upper and lower faces of the tie. In Fig. 6 an arm is shown having its extremity pointed, as at *j*, to enter the material of the tie. For the same purpose a nail or rivet *k* may be 80 employed. These auxiliary attaching means are not essential. In Fig. 5 the arms *c'* are shown of less length.

The spiral or twisted interengaging elements *d* serve to lock the rod sections against 85 disengagement and impart greater strength to that portion of the device than is otherwise attainable. It will be further noted

that the initial bends *l* of the arms are a mere continuation of the curves or bends of the end twists *d* and thus no such strain of the material is involved at this point as exists in prior structures which are inclined to transversely break at this point under great strain.

I claim:

In a reinforcing clamping member for

railroad ties, the combination of metallic 10 rods, interengaging spiral loops upon intermediate portions of the rods constituting the body of the member, and non spiral bendable end portions constituting clamping arms.

15

In testimony whereof I have affixed my signature.

GEORGE H. HARDMAN.
